METALLIC SHEET ROOFING

Oliver G. Burriss, Anderson, S. C., assignor of forty one-hundredths to E. P. Vandiver and forty one-hundredths to John C. Taylor, both of Anderson, S. C.

Application November 28, 1934, Serial No. 755,219

4 Claims. (Cl. 108—22)

My invention relates to improvements in metallic sheet roofing.

An important object of the invention is to provide a metallic sheet roofing element or shingle so constructed that it may be securely attached to the roof without the employment of separate attaching elements or clips, and which will interlock with a companion element or shingle for forming a water tight joint.

10 A further object of the invention is to so construct the roofing element or shingle that it may be quickly and conveniently moved into interlocking relation with the companion elements or shingles.

15 A further object of the invention is to provide means to collect and drain any water which may possibly pass the interlocking joints and ribs of the assembled elements or shingles, preventing the same from passing to the roof.

20 A further object of the invention is to provide a shingle of the above mentioned character which is extremely simple in construction and cheap to manufacture.

25 Other objects and advantages of the invention will be apparent during the course of the following description.

30 In the accompanying drawing, forming a part of this application, and in which like numerals are employed to designate like parts throughout the same,

Figure 1 is a plan view of a plurality of assembled roofing elements or shingles,

Figure 2 is a transverse section taken on line 2—2 of Figure 1,

35 Figure 3 is a perspective view of one of the roofing elements or shingles,

Figure 4 is an enlarged perspective view of the forward end of the shingle,

40 Figure 5 is a plan view of a modified form of shingle, and,

Figure 6 is an enlarged perspective view of the forward end of the modified form of shingle.

45 In the drawing wherein for the purpose of illustration are shown preferred embodiments of my invention, attention being called to Figures 1 to 6, inclusive, the numeral 10 designates a metallic roofing element or shingle, formed of sheet metal or the like, which may be suitably resilient. This metal shingle is provided at one longitudinal edge with a hollow rib or bead 11, which is preferably circularly curved in cross-section, and open at its ends and inner side, affording a longitudinal passage 12. This rib 11 is substantially semi-cylindrical and extends above the shingle 10 and has its open side arranged innermost with

respect to the shingle, so that the passage 12 is adjacent to the shingle. The hollow rib or bead 11 is formed by bending the material of the sheet 10 upon itself in an inward direction, forming an inner layer or sheet 13, and then bending the sheet upon the edge 14, back upon itself in an outward direction affording an outer sheet or layer 15, preferably snugly engaging the inner layer or sheet 13. The outer layer or sheet 15 is continued to a point substantially opposite the passage 12, as shown at 15' and is then bent horizontally to afford an attaching extension or flange 16, flush with the sheet 10 or body portion of the shingle. The attaching extension or flange 16 is provided with an upwardly bulging longitudinal rib 17, coacting with the hollow rib or bead 11, to afford a draining trough, for any water which may possibly pass over the hollow rib or bead 11. The attaching extension or flange 16 is preferably equipped with openings 18, for receiving nails or the like which are employed to securely connect the extension or flange 16 with the roof.

50 In the form of the invention shown in Figures 1 to 4, inclusively, the rib or bead 11 has its upper layer cut away along a transverse line 19, arranged at a right angle to the longitudinal axis of the bead or rib and along the longitudinal edge 14, leaving an extension 20, formed by the forward end of the inner layer 13. This extension 20 is preferably tapered forwardly, so that it may be readily passed into the rear end of the bead 11 of a companion shingle. The forward end of the attaching extension or flange 16 is foreshortened with respect to the forward end 30 of the shingle and terminates at a point 21, spaced rearwardly from such forward end of the shingle, but the forward end of the attaching extension or flange 16 extends forwardly for a substantial distance beyond the edge 19, there being a slot 22 between the edge of the forward projection of the extension or flange 16 and the tapered rib extension 20, as more clearly shown in Figure 4. The purpose of projecting the attaching extension or flange 16 beyond the edge 45 19 is to enable this projection to overlap the rear end of the attaching extension or flange of a companion shingle. In this form of the invention, the rear end 23 of the attaching extension or flange 16 is disposed at a right angle 50 to the longitudinal axis of the rib or bead 11 and the edge 23 terminates at or flush with the rear end of the shingle.

55 In the modification of the invention, as shown in Figures 5 and 6, the forward end or edge 24

of the attaching extension or flange 16 is disposed at a right angle to the longitudinal axis of the bead or rib 11 and terminates at or is flush with the edge 19, while the rear end of the 5 attaching extension or flange 16 projects rearwardly beyond the rear end of the shingle 10, terminating in a transverse edge 25, disposed at a right angle to the longitudinal axis of the rib or bead 11. The function of the extension at the 10 rear end of the attaching extension or flange 16 is to provide means whereby such rear extension of the attaching extension or flange may be passed beneath the forward end of the attaching extension or flange 16 of a companion shingle 15 and will thus overlap therewith. The construction shown in Figures 1 to 4, inclusively, is preferred as no additional metal is lost in providing the overlapping extension of the attaching extension or flange, but the form shown in Figures 20 5 and 6 will necessitate the loss of the sheet metal, corresponding to the length of the overlapping extension. The opposite longitudinal edge of the shingle 10 is bent to provide a hollow rib or bead 26, projecting above the same, and having its lower edge 27 substantially flush with the lower surface of the shingle and spaced therefrom, for affording a passage 28. The lower or forward end of the bead 26 is cut away from the point 27 to the free edge of the bead or rib, 30 affording a diagonal edge 29.

In assembling the shingles shown in Figures 1 to 4, inclusively, the lowermost or forward shingle 10 in one upstanding row is first placed upon the roof adjacent to the lower edge of the roof 35 so that the shingle shall suitably project below this lower edge and may be properly attached to the lower edge. The attaching extension or flange 16 of the forward shingle is now attached or nailed to the roof. The next shingle 10 in the 40 same row is now placed above or rearwardly of the first shingle, with the tapered inner layer or extension 20 disposed in the forward position. The next companion shingle to be placed in position may be slightly transversely inclined, and 45 the upper or rear end of the bead 26 of the forward or lower shingle will be guided into the lower or forward end of the bead 26 of the companion upper or rear shingle, by virtue of the diagonal edge 29. After the insertion has been 50 started, the next upper or rear shingle is swung down to a flat position upon the upper or rear end of the forward shingle, and the tapered extension 20 is inserted into the rear end of the rib 11. The upper or rear shingle is now moved 55 forwardly, and the edge 19 will snugly engage the rear end of the forward rib 11 of the forward shingle, and the outer portion of the bead or rib 11 of the forward shingle will enter the slot 22, while the forward extension of the attaching extension or flange 16 of the upper shingle 60 will be arranged upon and overlap the rear end of the attaching extension or flange 16 of the forward companion shingle. The rear shingle is now attached to the roof by nailing the extension or flange 16 to the same. It is thus seen that an exceedingly tight joint is effected between the ribs or beads 11 of the assembled shingles. Where the edge 19 engages the upper end 65 of the rib 11 of the forward shingle, such line of engagement is covered or spanned by the extension 20, and the adjacent ends of the attaching extension or flanges 16 overlap, rendering it impossible for water to pass these extensions or flanges, and the slot 22 is closed by the outer 70 portion of the bead or rib of the forward shingle,

thus affording an exceedingly tight joint for any water which may pass the ribs 11 at this point, such water being conducted off by the trough formed by the ribs 17 and beads or ribs 11. In laying the next row of shingles the hollow rib or bead 26 of the shingle is passed over the assembled ribs or beads 11 and the shingle is moved forwardly to break joint with the overlapped ends of the assembled shingles in the completed row. The next rear shingle in the second row is applied in a similar manner so that its forward end will overlap the rear end of the companion shingle in the same row, and the forward extension of its attaching extension or flange 16 will overlap the rear end of the attaching extension of the last forward shingle. The attaching extensions of these shingles are, of course, nailed or attached to the roof. In a similar manner each row of shingles is completed and any desired rows of shingles may be assembled. The row of shingles next to the end of the roof is cut off and bent over the end of the roof and nailed thereto. It is thus seen that the shingles are securely attached to the roof without the use of separate clips. As before stated, the ribs 17 coat with the 25 assembled ribs or beads 11 for providing a trough to conduct away any water which may possibly pass the assembled beads or ribs 11. The particular advantage in my construction is that the attaching extensions or flanges 16 are permanently secured to the shingles and will, therefore, be readily nailed to the roof. Where detachable clips are used workmen frequently fail to use a sufficient number of these clips, whereby the shingles are not securely attached to the roof. 30

The shingles shown in Figures 5 and 6 are assembled in a similar manner, and the ends of the attaching extensions or flanges overlap, the difference being that the extension of the attaching flange is carried at the rear end of the 35 forward shingle, instead of at the forward end of the rear shingle.

It is to be understood that the forms of my invention herewith shown and described are to be taken as preferred examples of the same and 40 that various changes in the shape, size and arrangement of parts may be resorted to without departing from the spirit of my invention or the scope of the subjoined claims.

Having thus described my invention, what I 45 claim is:

1. A metallic shingle having its material at one longitudinal edge bent over the same for affording a longitudinal hollow bead, said bead having inner and outer layers and an inner 50 longitudinal edge spaced from the upper surface of the shingle for affording a longitudinal passage, an attaching extension permanently secured to the outer layer and having its forward end foreshortened and spaced from the forward end of the shingle, said bead having 55 its outer layer near its forward end cut away for providing a transverse edge spaced rearwardly from the forward end of the shingle, said attaching extension projecting forwardly beyond said transverse edge, the inner layer projecting forwardly beyond the transverse edge of the upper layer for providing a bead extension, the forward projection of the attaching extension being separate from the bead extension, the rear end of said bead having a transverse edge, 60 said shingle being provided at its opposite longitudinal edge with a hollow rib having a longitudinal passage.
2. A metallic shingle having its material at one 65

- longitudinal edge bent over the same for affording a longitudinal hollow bead having inner and outer layers and an inner longitudinal edge spaced from the upper surface of the shingle for 5 affording a longitudinal passage, an attaching extension permanently secured to the outer layer and having its forward end foreshortened and spaced from the forward end of the shingle, said bead having its outer layer near its forward end 10 cut away for providing a transverse edge spaced rearwardly from the forward end of the shingle, the rear end of the bead having a transverse edge, the attaching extension projecting longitudinally beyond one end of the outer layer of 15 the bead, the inner layer of the bead projecting forwardly beyond the transverse edge of the upper layer to provide a bead extension, said shingle being provided at its opposite longitudinal edge with a hollow rib having a longitudinal passage. 20 3. A metallic shingle having its material at one longitudinal edge bent over the same for affording a longitudinal hollow bead having inner and outer layers and an inner longitudinal edge spaced from the upper surface of the shingle for 25 affording a longitudinal passage, an attaching extension permanently secured to the outer layer and having its forward end foreshortened and arranged at generally a right angle to the longitudinal axis of the bead and spaced from the forward end of the shingle, said bead having its outer layer near its forward end cut away for providing a transverse edge spaced rearwardly from the forward end of the shingle and disposed generally at a right angle to the longi- 30 35
- tudinal axis of the bead, said attaching extension projecting forwardly beyond said transverse edge, the inner layer of the bead projecting forwardly beyond the transverse edge of the upper layer to provide a bead extension, said projection of the attaching extension being spaced from the bead extension for providing a slot, the rear end of said bead having a transverse edge disposed generally at a right angle to the longitudinal axis of the bead, said shingle 10 being provided at its opposite longitudinal edge with a hollow rib having a longitudinal passage. 15 20 25 30 35
4. A metallic shingle having its material at one longitudinal edge bent over the same for affording a longitudinal hollow bead having inner and outer layers and a longitudinal passage, an attaching extension permanently secured to the outer layer and having its forward end foreshortened and arranged at a point spaced from the forward end of the shingle, said bead having its outer layer near its forward end cut away for providing a transverse edge spaced rearwardly from the forward end of the shingle and disposed generally at a right angle to the longitudinal axis of the bead, said attaching extension 20 25 30 35
